VENETIAN BLIND

William Wade, Chicago, and Edwin North, Rockford, Ill., assignors to National Lock Company, Rockford, Ill., a corporation of Delaware

Application January 28, 1937, Serial No. 122,794

12 Claims. (Cl. 156—17)

This invention relates to Venetian blinds and supporting and operating mechanism therefor, the present disclosures being in part a continuation of the matter disclosed in applicant's co-pending application Serial No. 122,793, filed Jan. 28, 1937.

Generally stated, it is an object of the present invention to provide a novel supporting means for a blind structure, and one which may be readily installed and which will facilitate the quick and effortless mounting of the main blind unit in its operative position.

More particularly stated, the invention provides among its other objects, novel bracket members adapted for attachment to a window casing and having a main blind-supporting carriage removably mounted therebetween with pin-and-slot engagement between the brackets and carriage, which permits a limited sliding movement or translation of the latter between the brackets so that variations in window width may be compensated.

A still more specific object is the provision of a supporting carriage having a pivoted roller housing with lug formations adapted to fit into elongated slots in a mounting bracket so as to permit limited axial movement of the carriage between the sides of the window while at the same time preventing lateral displacement of the carriage from the brackets.

Other advantages and novel aspects of the invention will appear as the following description proceeds in view of the drawing, in which:

Fig. 1 is a front elevation of the blind supporting means;

Fig. 2 is an enlarged perspective fragment of the carriage, roller housing and bracket;

Fig. 3 is an enlarged horizontal section through the bracket but showing the interior of the housing in plan, the view being taken along lines 3—3 of Fig. 1;

Fig. 4 is an enlarged vertical side section through the housing and rollers and is taken along lines 4—4 of Fig. 3;

Fig. 5 is an enlarged horizontal section through the housing and pay hole and is taken along lines 5—5 of Fig. 3;

Fig. 6 is a vertical section through the housing along line 6 of Fig. 3 looking into the pay hole; while

Fig. 7 is a perspective fragment of the rim and slot pivotal mounting for the right-hand end of the carriage.

As seen in Fig. 1, the blind assembly includes a main bracket 19 and a second bracket 12 at-

tached to the respective upper corner portions of a usual window casing 14, the attachment being effected by the use of screws if desired.

Extended horizontally between the brackets is a carriage or top rail 16 having at its (right-hand) one extremity a pin and slot engagement 17—19 with a pivotal member 15 on bracket 12 with which the carriage may be supportably engaged or disengaged by a simple sliding or translation in an axial direction toward and away from the bracket 12.

At the opposite (left-hand) end of the carriage 16 is a roller and mounting housing 18 (Figs. 1 and 2) pivotally attached to the end of the carriage by means of a stud sleeve 20 15 clamped or peened into the side wall 22 of housing 18 and into an upturned end wall 24 of the carriage 16.

Thus, the housing 18 is rotatable in a direction about the main axis of the carriage. In point of fact the axis of the opening 21 and the axis of pivot of the right-hand end of the carriage relative to its bracket 12 are in alignment or co-extensive, so that the carriage may be said to pivot about an axis through the pay-hole or sleeve 20 when the housing is held stationary in the manner hereinafter to be described.

As seen in Figs. 3 and 4 particularly, the housing 18 is provided interiorly with a pair of rollers 26 and 28, the former being disposed with its axis of pivot vertical, while the latter (roller 28) rotates about a horizontal axis and is positioned beyond the forward edge of the bottom 23 between extended opposite side wall 35 portions 60—61 so as to expose the horizontal roller for passage thereover or control cords or chains 30 in order that the chains may pass around the vertical roller, through the pay-hole openings 21 in sleeve 20, into the carriage for distribution over rollers 17 thereon, from whence the chains 30 descend for supporting engagement with blind slats 32.

Manipulation of chains 30 is facilitated by the attachment thereto of a common pull-chain 34 45 by means of which the chains may be raised and lowered over the housing and carriage rollers to effect a corresponding movement of the slats.

Preferably, the pivotal attachment of housing 18 to the carriage 16 is such that there is a movement in an anti-clockwise direction, as seen in Fig. 2, due to the eccentric weight of the rollers 26 and 28 and the chains. There is a tendency normally, therefore, of the housing 55

to fall pivotally downward in the direction of the pull-chain 34. The reason for this will shortly appear.

The brackets 10 and 12, generally speaking, 5 may be provided with rectangularly disposed wall portions adapted to fit flush into the corner of the window casing.

Bracket 10, however, has a horizontally extended plate 36 with an angled end portion or 10 flange 38 disposed in a vertical plane and provided with an elongated slot 40 extended in the direction of the axis of pivotatation of the carriage 16 and positioned close to the upper horizontal surface of the seating plate 36. Spaced 15 away from slot 40 in a direction transverse to the carriage axis (and hence to the axis of slot 40) is a second slot 42 in plate 36. This slot 42 is also somewhat elongated and has its long axis disposed substantially parallel to that of slot 40 20 and hence to the major axis of the carriage unit. It may be noted that slot 40 opens into a vertical plane while slot 42 opens into a horizontal plane, but their respective axes are parallel. It is also to be pointed out that the rear slot 40 25 is very close to the horizontal top surface of the bed or seating plate 36. The importance of this feature will appear in the following paragraphs.

In Fig. 2, it will be observed that the housing 18 has its bottom wall 23 provided with a co- 30 extensive tail lug 50 and a depending forward or drop lug 52. The tail lug is stamped out in the formation of the housing and is of a length less than the length of the rear or tail slot 40. The drop lug 52 on the other hand is punched out 35 of the bottom 23 with its major axis transverse to that of the second or forward drop slot 42, and being of a width along this axis adequate to permit the lug to drop easily into slot 42. The shifting or axial translation of drop lug 52 in drop slot 42 is limited only by the thickness 40 of the lug and the width of the tail lug 50 relative to the length of its slot 40. This is one of the important features of the invention.

The lengths of the tail slot 40 and drop slot 45 42 are dimensioned relative to their respective lugs to permit a limited amount of shifting or translation of the housing 18 (and hence the carriage 16) in the direction of the main long axis of the carriage unit, it being recalled that the right-hand end of carriage 16 is movably 50 supported by its bracket 12 in a manner to permit such axial displacement.

One of the objects of this invention being the provision of a simple blind supporting structure 55 which can readily be installed and which can be dismounted for cleaning purposes without the use of tools or special skill, it will be apparent that after the brackets 10 and 12 are in place, the carriage 16 can be mounted quite simply by moving its right-hand end toward bracket 12 and 60 the pivoted arm 15 thereon so as to place the pins 19 into openings 17 in the carriage end wall. Thereafter the left-hand end of the carriage and housing 18 (now manually tilted as shown in Fig. 2) are swung into place on the seat or 65 bearer plate 36 of bracket 10.

As the carriage is thus moved easily into place, the tail lug 50 moves naturally into its slot 40, and as soon as this happens, the rear bottom edge of the housing bears against the flange 38, 70 whereupon the backward movement of the carriage unit and housing is halted and the momentum thereof translated into a pivotal movement of the housing 18 about its sleeve stud 20 so that the bottom 23 of housing 18 quickly and 75 without noticeable effort falls down against the

bearer plate 36 and the depending drop lug 52 naturally falls into its slot 42.

In the foregoing mounted position, it is again to be observed that the carriage 16 may be shifted or translated axially from left to right between the brackets 10 and 12 by virtue of the disposition of lugs 50 and 52 in the axially elongated slots 40 and 42, thus variations in window casing width may be compensated.

Since clearances between the blind structure 10 and window casing are desirably held to a minimum, it is an advantage also to have the housing 18 drop naturally because then the tail is pointed upwardly toward its goal as the left end of the carriage is moved into place and the tendency of the housing to pivot downwardly facilitates the registration of the pin and slot members.

In order to limit the pivoted movement of the housing 18 so as to avoid tangling the chains 20 and to position the housing most advantageously for mounting, the inner collar portion of the sleeve stud 20 in wall 21 is provided with a radially extensive stopping lug 56 against which the inner bottom surface of the housing will abut 25 to limit pivotal movement of the same so that its movement in a clockwise direction will be stopped at the position shown in Fig. 2.

It will be apparent that the housing itself may 30 assume a variety of forms and be constructed in various ways. In the illustrative embodiment, it includes the bottom wall 23 of substantially quadrangular shape and having a pair of oppositely disposed and integrally formed side walls 60, 61, a rear end wall 62, a forward open side 35 63, and a curved cover plate 64.

The roller 28 is pivoted between the extended side walls 60-61 at a point beyond the forward edge of the bottom 23, and the bottom part of the curved cover plate 64 is provided with a pair of inturned ears 65 which are positioned adjacent the axial extremities of roller 28 to limit the 40 swing of chains 30. The top edges of the side walls 60-61 and rear wall 62 are slotted to receive ears 66 on the cover plate. Likewise the cover plate 64 is slotted to receive ears 67 on 45 the housing, only one screw 68, threaded into the fixed spindle 69 of roller 28 being necessary to secure the cover plate 64 in place.

Having thus described the manner in which the several important objects of the invention 50 are achieved, it will be evident that various modifications and arrangements of the foregoing structure may be made without departing from the spirit and intent of the invention, and it is to be understood that all such changes are intended to be included within the scope of the 55 appended claims.

Having thus described our invention, what we claim as new and desire to protect by Letters Patent is:

1. In a Venetian blind, a carriage supported 60 axially between opposite end brackets attached to a window casing or the like, one of said brackets having pin means extended in an axial direction toward said carriage and receivable in the axial end of the same, the other said bracket having a member with axially elongated slots therein, the corresponding end of said carriage having a pivoted member with lug means receivable in said last-mentioned slots, and said carriage being movable axially between said brackets.

2. In a Venetian blind, a carriage pivotally supported between a pair of brackets, one of said brackets having axially-directed pin and slot en- 70 75

gagement with one axial end of said carriage whereby the latter is free to shift in an axial direction, the other said bracket being provided with slots elongated in the direction of the pivotal axis of the carriage, and the latter having a pivoted member provided with pins receivable in said last-mentioned slots and movable therein in an axial direction to permit shifting of the carriage as aforesaid.

10 3. In a Venetian blind, an elongated blind-supporting carriage mounted between axial end brackets, one said bracket having axially extensive pin and slot supporting engagement with an axial end of said carriage to permit an axial shifting of the same relative to said bracket, the opposite end of said carriage having a member pivotable in a direction about the axis of the carriage, a second bracket disposed adjacent said last-mentioned pivotable member and supportably engaging the same by pin and axially elongated slot means extended laterally relative to the axis of pivotatation of said pivotable member whereby said carriage may be axially shifted between said brackets.

25 4. In a Venetian blind, an elongated slat-supporting carriage mounted for pivotal movement about its long axis between a pair of end brackets, one of said brackets having pin means extending axially into an end of said carriage and the latter being movable on said pin means in an axial direction, the other bracket of said pair having a horizontally disposed member with a vertical portion and having a slot disposed in each of the horizontal and vertical portions thereof, said carriage having pin means receivable in the slot portions of said last-mentioned other bracket and freely movable in said slot portions in the direction of the axis of the carriage whereby the latter may be mounted in window casings of varying width.

30 5. In a blind structure, an elongated slat-supporting carriage and means for mounting said carriage for movement of the same in the direction of its long axis, said means including a pair of brackets positioned at the axial extremities of the carriage and each having pin-and-slot engagement therewith, the said slot parts being axially elongated and the said pins being movable in their respective slots in an axial direction.

45 6. In a blind structure, an elongated slat-supporting carriage and means for mounting said carriage for movement of the same in the direction of its long axis, said means including a pair of brackets positioned at the axial extremities of the carriage and each having pin-and-slot engagement therewith, the said slot parts being axially elongated and the said pins being movable in their respective slots in an axial direction, the pin means of one said bracket being extended 50 in an axial direction relative to said carriage, while the pin means of the other bracket of the pair is extended in a direction laterally of said axis.

55 7. In a blind structure, an elongated slat-supporting carriage and means for mounting said carriage for movement pivotally about its long axis and also longitudinally of said axis, said means including a pair of brackets positioned respectively at the axial extremities of the carriage, one said bracket having a pivoted member with axially extended pin means supportably engaging an axial end of the carriage and the latter being movable thereon toward and away from said bracket, said carriage having a pivoted member at its opposite axial end and movable in a

direction about said axis, said pivotable member having pin members extended substantially at right angles to one another and laterally of the axis of said carriage, the other bracket of said pair having axially elongated slots adapted to receive said last-mentioned pin members and permit movement thereof in the direction of the long axis of the carriage when the latter is shifted longitudinally.

10 8. In a blind structure, an elongated slat-supporting carriage and mounting means therefor including a bracket positioned at each of the axial extremities thereof, pin and slot means for mounting one end of said carriage on one of said brackets for movement relative thereto in an axial direction, said carriage having a roller housing pivotally attached to an opposite end of said carriage, the correspondingly positioned one of said brackets having a surface portion on which said housing is adapted to rest, together with pin and slot means on said housing and bracket for limiting the relative movement of the latter to the former in a direction lateral to the said carriage axis, but permitting such movement longitudinally of said axis.

25 9. In a blind structure, an elongated carriage, slats suspended in spaced relation from said carriage by elongated flexible members, and means for mounting said carriage for movement both along and about its long axis, said means including a first bracket positioned at one axial extremity of said carriage, a pivoted member on said bracket and having carriage supporting means extended therefrom axially toward said carriage and the latter slidably engaging said last-mentioned supporting means for movement toward and away from said bracket, a housing pivotally mounted on the opposite end of said carriage for movement in a direction around the axis thereof, said housing having a lug depending from the bottom thereof and a second lug co-extensive with said bottom, a second bracket positioned at said last-mentioned end of the carriage and having a horizontal surface with a first lug-receiving aperture therein and also having a surface disposed vertically and having a second lug-receiving aperture, both of said last-mentioned apertures being elongated axially of said carriage and the latter being mounted with the said bottom of the housing seating upon said horizontal surface of the bracket with the said depending lug disposed in the first said aperture and the said co-extensive lug disposed in the said second vertical aperture.

40 10. In a blind structure, an elongated carriage, slats suspended in spaced relation from said carriage by elongated flexible members, and means for mounting said carriage for movement both along and about its long axis, said means including a first bracket positioned at one axial extremity of said carriage, a pivoted member on said bracket and having carriage supporting means extended therefrom axially toward said carriage and the latter slidably engaging said last-mentioned supporting means for movement toward and away from said bracket, a housing pivotally mounted on the opposite end of said carriage for movement in a direction around the axis thereof, said housing having a lug depending from the bottom thereof and a second lug co-extensive with said bottom, a second bracket positioned at said last-mentioned end of the carriage and having a horizontal surface with a first lug-receiving aperture therein and also having a surface disposed vertically and having a second lug-re-

- ceiving aperture, both of said last-mentioned apertures being elongated axially of said carriage and the latter being mounted with the said bottom of the housing seating upon said horizontal
- 5 surface of the bracket with the said depending lug disposed in the first said aperture and the said co-extensive lug disposed in the said second vertical aperture, said housing having roller means over which said flexible suspending members pass.
- 10 11. In a blind, an elongated carriage, blind members suspended by chains from said carriage, a first bracket disposed at one axial end of said carriage, means on said bracket supportably en-
- 15 gaging the carriage for both pivotal and axial movement, a box-like housing pivotally attached to the opposite end of said carriage and movable in a direction about the axis of the latter, means for limiting the pivotal movement of the housing,
- 20 21. a bracket having a surface on which said housing is adapted to rest and having an axially extensive opening in said surface together with a portion extended at an angle to said surface and provided with a second axially extensive opening,
- 25 22. said housing having roller means on which said chains are arranged to move to raise and lower said blind members, said housing further having

lug means receivable in said first and second openings whereby said housing may move in an axial direction on said bracket surface, but not laterally thereon.

12. In a blind, an elongated carriage, slats 5 movably suspended in spaced relation therefrom, means for supporting one end of said carriage for movement in a direction around its long axis and also longitudinally of said axis, a roller housing pivotally attached to said carriage at its opposite extremity and movable in a direction about said axis, a bracket having a horizontally extended surface with an angularly extended edge flange, said surface having an axially extensive drop opening therein, said flange also having an 15 axial tail opening positioned close to said horizontal surface, said housing having a bottom portion adapted to rest on said horizontal surface and said bottom being provided with a depending drop lug and a co-extensively directed tail lug, 20 the latter being receivable in said flange opening and said drop lug being receivable in said drop opening by pivotal movement of said housing downwardly when said tail lug is positioned in said tail slot.
